UNITED STATES PATENT OFFICE.

EDWARD R. STILES, OF LITCHFIELD, ILLINOIS.

WEATHER-STRIP FOR CAR-DOORS.

SPECIFICATION forming part of Letters Patent No. 381,037, dated April 10, 1888.

Application filed December 31, 1887. Serial No. 259,515. (No model.)

To all whom it may concern:

Be it known that I, EDWARD R. STILES, of Litchfield, in the county of Montgomery and State of Illinois, have invented certain new and useful Improvements in Weather-Strips for Car-Doors; and I do hereby declare the following to be a full, clear, and exact description of the invention, such as will enable others skilled in the art to which it pertains to make and use it, reference being had to the accompanying drawings, which form part of this specification.

My invention relates to an improvement in weather-strips for car-doors; and it consists in the combination of a recessed door-post which faces at right angles to the movement of the door and a weather-strip which is placed in a recess in the post, and which, when left free to move, drops down of its own weight against the inner side of the closed car-door, as will be more fully described hereinafter.

The object of my invention is to provide a weather-strip for the doors of freight-cars, so as to prevent water and cinders from being driven into the car through the openings between it and the door when the door is closed.

Figure 1 represents a side elevation of a weather-strip embodying my invention. Fig. 2 is a horizontal section taken on the dotted line 1 1 of Fig. 1. Fig. 3 is a slight modification. Fig. 4 is a horizontal section taken on the dotted line 2 2 of Fig. 2.

A represents the body of the car; B, the door-post, and C the ordinary sliding door, which moves along the outside of the car and closes the opening in its side in the usual manner. Each of the door-posts is provided with a suitable recess or groove, D, in which the weather-strip G is placed. This strip may either be provided with arms or lugs J, which catch between pins O in the door-post; or the strip may be connected to the post by means of links I, just as may be preferred. The lower ends of the strips have extensions Q formed upon them, and which extend at a suitable angle to the length of the strip, as shown. These extensions pass down through suitable slots in the side sill of the car and

project below the door just far enough to be freely operated by hand. The links or the lugs, when the strip is pushed upward from its lower end, cause the strip to close into the recess in the door-post, and when the strip is left free to move it sinks downward and outward, so as to strike against the inner side of the door, and thus closes the opening between the inner side of the car and the inner side of the door, so as to prevent water, dust, and cinders from beating into the car.

Through the lower ends of the extensions Q on the strips are made holes R, so that when forced upward and backward they may be held in that position by means of the hooks S, or other suitable catches for that purpose. Before the door is opened or closed the strip should be forced upward and backward, so as to be moved out of contact with the door, and thus leave the door free to slide back and forth without the danger of injuring the strips. As soon as the door is closed these stops are freed from their supporting hooks, or other similar devices, and then the strips sink downward from their own weight against the inner side of the door.

Having thus described my invention, I claim—

1. The combination of the car-body, the door-posts suitably recessed, and the weather-strips placed in the recesses and standing at a right angle to the door, with the sliding car-door, against the inner side of which the strips close, substantially as shown.

2. The combination of the car-body, the door-posts suitably recessed, and the weather-strips provided with extensions Q, which extend down outside of the body of the car, and which are placed in the recesses in the door-post, and suitable hooks or devices for holding the strips, with the sliding door, against the inner sides of which the strips close, substantially as described.

In testimony whereof I affix my signature in presence of two witnesses.

EDWARD R. STILES.

Witnesses:

JOHN M. FERGUSON,
THEO. LOESCHEN.
